UNITED STATES PATENT OFFICE

CHARLES HARTMAN, OF WADDINGTON CHANNEL, BRITISH COLUMBIA, CANADA

PIPE WRENCH

Application filed November 13, 1928. Serial No. 319,036.

This invention relates to improvements in pipe wrenches of the sliding jaw type, and consists in the construction, combination and arrangement of parts as herein described and 5 claimed.

The object of the invention is to provide a device of the type described, which possesses a small number of easily manufactured and assembled parts which will not get out of order and which can be easily and cheaply replaced on occasion.

A further object of the invention is to provide a device of the type described which has no projecting parts upon the back thereof 15 and which consequently can be inserted into constricted places and used where existing types of such wrenches cannot be efficiently used.

The invention resides chiefly in the elimination of the usual outermost jaw-ended pivotal rack and the making of the outer jaw rigid with the lever handle, the corresponding opposing jaw member being made transversely slidable outwards in a guide against 25 the action of a spring and with uniform angularity with the opposite jaw.

The invention is more specifically described and illustrated in the accompanying drawings which are attached to and form part of 30 this application, and in which:

Figure 1 is an edge view of the device.

Figure 2 is a side view of the same.

Figure 3 is a section of the sliding jaw taken on the line 3—3 in Figure 2.

Figure 4 is a plan of the sliding jaw as shown in Figure 3.

In these views the numeral 5 indicates the stock or handle of the tool, terminating in the fixed jaw 6 which is serrated in order to provide a grip upon a pipe or object of circular section. The stock 5 is intermediately extended laterally at 7 to form a hollow guide of rectangular section for the sliding member 8, which moves in a recess 9 formed in the 45 inner edge of the stock 5.

The member 8 has cut upon its edge a thread or rack 19 which is adapted to be engaged by a worm 10 rotatably mounted in bearings 11 in the stock 5. The rotation of the worm 10 by the finger of the operator 50 causes the member 8 to move longitudinally with respect to the stock 5 and thus to approach or recede from the fixed jaw 6.

The member 8 carries slidably mounted upon its upper side a jaw member 12 which 55 can move transversely across the end of the member 8 and which is grooved, as shown in section in Figure 3, and further secured by the screw 13 so that while free to slide transversely, it cannot be detached from the member 8 when assembled for use.

The jaw member 12 is serrated similarly to the fixed jaw 6, and forms the complementary or opposing contact member whereby the pipe or other object is gripped between the jaws of the device. The jaw member 12 is further inclined to the jaw 6 so that a gripping effect is provided between the jaws when pressure is put upon the handle 5.

The jaw 12 is kept at the end of its travel 70 furthest from the stock 5 by means of the leaf spring 14, which is anchored by the screw 15 to the member 8, and passes through the guide 7, its free end engaging at 16 with the jaw 12. When, however, the tool is caused 75 to grip a pipe or like object between the jaws 6 and 12, the jaw 6, as a result of the pressure, slides toward the stock 5 until the projection 17 abuts against the bottom of the recess 18 in the stock 5, thus causing the jaws 80 6 and 12 to tighten upon and firmly grip the object between them.

The initial distance between the jaws 6 and 12 is easily and quickly set for any particular size of pipe within the range of the 85 device by means of the worm 10 and rack 18, after which the device is used in the manner of a pipe wrench to grip and rotate any object placed between the jaws 6 and 12.

The operation of the tool is such that in 90

consequence of the angularity between the jaws being constant in value, and the jaw itself being slidable in a guide, the general action is more precise and therefore more definitely under control than with the common form of pipe wrench.

Having now fully described my invention, what I claim and desire to be protected in by Letters Patent, is:

- 10 1. In a pipe wrench comprising a lever member having at its extremity a right angular upturned inwardly serrated jaw, a transverse aperture for the reception of a worm, and a longitudinal tubular aperture and slideway for the reception of a slidable rack adapted to engage said worm, the combination of a slidably movable serrated jaw member angularly disposed to and opposing the corresponding serrated portion of the upturned extremity of said lever member, a grooved slideway on the transverse end surface of said slidable rack adapted to engage said movable jaw member, spring means on said slidable rack tending to slide said movable jaw outwardly along said end grooved slideway and against a removable stop on said movable jaw, all substantially as described herein.
- 15 2. In pipe wrenches, a stock or handle member having integrally formed therewith a fixed jaw at one end and a lateral extension adjacent said fixed jaw and spaced therefrom, said lateral extension having a longitudinal passage therethrough and a transverse aperture to one side of and communicating with said passage, a worm mounted in said transverse aperture, a rack bar sliding in said longitudinal passage and of greater length than the length of said passage and having a rack
- 20 30 35 40 45 50 portion engaging said worm, said rack bar having movement in said longitudinal passage longitudinally and also laterally toward and from said worm, a movable jaw member slidably mounted on that end of said rack bar which is adjacent said fixed jaw to slide in and out toward and from said stock, means to limit the outward sliding movement of said movable jaw member, and a single means continuously tending to move said slidable jaw member away from said stock.
